UNITED STATES PATENT OFFICE

171,959

ROBOTIAN-LIKE COSTUMED FIGURE

Ernest Walling, New York, N. Y., assignor, by
mesne assignments, to Westinghouse Radio
Stations, Inc., Washington, D. C., a corporation
of Indiana

Application May 27, 1953, Serial No. 25,216

Term of patent 14 years

(Cl. D34—4)

To all whom it may concern:

Be it known that I, Ernest Walling, a citizen of the United States, residing in New York city, in the State of New York, have invented a new, original, and ornamental Design for a Robotian-Like Costumed Figure, of which the following is a specification: reference being had to the accompanying drawings, forming a part thereof in which:

Fig. 1 is a front elevational view of the robotian-like costumed figure embodying my new design with a portion of the head cut away for illustrative purposes;

Fig. 2 is a plan view showing the robotian-like costumed figure;

Fig. 3 is a rear elevational view showing the robotian-like costumed figure; and

Fig. 4 is a side elevational view thereof.

I claim:

The ornamental design for a robotian-like costumed figure, as shown.
